CIRCUIT BREAKER

James M. Cumming, Turtle Creek, Pa., assignor to
Westinghouse Electric Corporation, East Pittsburgh, Pa., a corporation of Pennsylvania

Application August 24, 1943, Serial No. 499,800

11 Claims. (Cl. 200—82)

The invention relates to circuit breakers and, more particularly, to circuit-breaker operating mechanisms of the pneumatic type.

Circuit breakers for electrical power systems are desired which operate at very high speed and in which the motion of the parts can be quickly reversed in order to obtain quick interruption and quick reclosing of the electrical circuit. It is, therefore, highly desirable to eliminate as far as possible the factors which tend to delay operation of the breaker. Where a pneumatic type operating mechanism is employed for operating a circuit breaker, back pressure in the cylinder tends to retard the speed of operation and some means must be provided to quickly remove the back pressure. The valve means for controlling fluid flow should provide for adequate fluid flow and should operate very quickly despite the limitation of small available electrical control energy. The usual types of three-way valves for admitting fluid pressure to the cylinder and venting the cylinder have not been found satisfactory for pneumatic circuit-breaker operating mechanisms for various reasons. They are too slow in operation, do not provide adequate intake and exhaust flow, and require too much electrical control energy.

An object of the present invention is the provision of a circuit breaker with an improved operating mechanism of the pneumatic type capable of effecting quick high-speed operation of the circuit breaker and moving parts.

Another object of the invention is the provision of a circuit-breaker operating system of the pneumatic type embodying an improved quick-acting intake and exhaust valve-mechanism whereby quick response and high-speed operation of the circuit breaker and its operating means are obtained.

Another object of the invention is the provision of a circuit-breaker operating mechanism of the pneumatic type with an improved quick-acting automatic intake and exhaust valve-mechanism, of simple and inexpensive construction, which provides for high-speed operation and reversal of the operating mechanism and which requires only a small amount of electrical control energy.

The novel features that are considered characteristic of the invention are set forth in particular in the appended claims. The structure and mode of operation of the invention, together with additional objects and advantages thereof will be best understood from the following detailed description of one embodiment thereof when read in conjunction with the accompanying drawing, in which:

Figure 1 is a view, partly in section, of a circuit-breaker operating mechanism embodying the present invention, the circuit breaker being shown somewhat schematically, and

5 Fig. 2 is a fragmentary view, partly in section, showing the dump-valve which is controlled by the trip device.

The present invention is illustrated as applied to a pneumatic circuit-breaker operating mechanism similar to that disclosed in the copending application of James M. Cumming and Richard C. Cunningham, Serial No. 410,686, filed September 13, 1941, and assigned to the same assignee as the present invention.

15 Referring to Fig. 1 of the drawing, the circuit breaker represented very schematically at 1, may be of any conventional type either of the oil break, air break or gas blast type. As schematically shown, the circuit breaker comprises stationary contact means 9, and cooperating movable contact means 11. The circuit breaker is biased to open-circuit position by spring means 15, and is operatively related to the operating mechanism indicated generally at 17 by any suitable connecting means represented schematically as comprising a lever 19 pivoted at 21 and pivotally connected at one end to the breaker rod 23 and at its other end to an operating rod 25 which is in turn connected to the operating mechanism 17.

20 The operating mechanism comprises a main casting 27 formed to provide a cylinder 29 which is closed at its upper end by an integral part of the casting. A closure member 31 is secured to the bottom of the cylinder, this closure member having a relatively large port 33 therein open to the atmosphere. An operating or latching lever 35 consisting of a pair of spaced parallel levers is pivotally mounted at one end on the casting

25 27 by means of a pair of links 41 pivoted on the casting by a pivot-pin 44. Only one of the links 41 and one of the parallel levers is visible in Fig. 1. Part of the operating lever and part of the cylinder casting have been broken away to reduce the width of the figure. The free ends of the parallel levers comprising the operating lever 35 are connected by a cross member and carry a short shaft 45 therebetween on which is rotatably mounted a latching roller 47.

30 40 The breaker-operating rod 25 is pivotally connected by a pivot pin 49 to the midpoint of the operating lever 35. The breaker-operating lever is adapted to be held in closed position to hold the circuit breaker closed by means of a high-speed latching mechanism comprising a main

latch 51 of the slip-off type, and an auxiliary holding latch 67. The main latch 51 is pivoted on the casting 27 by a pivot pin 53 and its latch end is adapted to engage the latch roller 47 of the breaker operating lever 35. The latch 51 is biased to latching position by a spring-pressed plunger 57. The auxiliary latch 67 is pivoted on the casting by a pivot pin 69 and is biased by a spring 75 to engage and hold the main latch in latching position. A projection 77 of the auxiliary latch extends directly over the upper end of the trip plunger 79 of an electromagnetic trip device 81.

The trip device 81 comprises, in addition to the trip plunger, an E-shaped core 83 of magnetic material, an energizing winding 85 mounted on the center leg of the core, and a movable armature 87 for moving the trip plunger upwardly to release the latching means and thereby trip open the circuit breaker.

The trip plunger slidably extends upwardly through a guide opening in the center leg of the core 83 and through an opening in the horizontal shelf portion of the casting 27 on which the core 83 is supported by brackets. A spring 89 biases the armature 87 downwardly to unattracted position.

The trip device 81 may be energized by a conventional trip circuit upon the occurrence of predetermined abnormal conditions such as an overload in the circuit controlled by the breaker and also by a manual trip control switch. When the trip device is energized, the armature is moved upwardly causing the trip plunger 79 to disengage the auxiliary latch 67 from the main latch 51 whereupon the accelerating spring 15 moves the circuit breaker to open position at high speed. A balance lever 95 pivoted on the pivot pin 69 is provided for holding the auxiliary latch 67 in released position as shown as long as the operating lever 35 is away from the latched position, so that the latch roller 47 can push back and pass the main latch 51 when the circuit breaker is reclosed. The balance lever 95 is biased in a counterclockwise direction by a spring 97, stronger than the auxiliary latch spring 75, and has a projection 99 which extends beneath the auxiliary latch extension 77. The balance lever also has a projection 101 which is adapted to be engaged by the free end of the breaker-operating lever 35 to hold the balance lever down in inoperative position when the operating lever is in closed and latched position.

An operating piston 103 is reciprocably movable in the operating cylinder 29, and this piston has a piston rod 107 which slidably extends in a fluid-tight manner through an opening provided therefor in the top wall of the cylinder. The upper end of the piston rod has a connecting element 109 pivotally connected to the pivot pin 49 on the breaker-operating lever 35. The piston 103 is thus operatively connected to the circuit breaker and operating lever.

The operating piston 103 is adapted to be moved downwardly in the cylinder 29 to close or automatically reclose the circuit breaker, by compressed gas such as compressed air stored in an auxiliary air reservoir or tank 111. Compressed air from the tank 111 is admitted into the upper end of the cylinder 29 by a control valve device indicated generally at 113 which will be hereinafter described. Compressed air is stored and maintained at a predetermined pressure in the tank 111 from a large main reservoir (not shown) sup-

plied by a conventional motor-driven compressor unit (not shown).

In order to provide for quick reversal and very high-speed initial opening movement of the operating piston 103 and circuit breaker 7 to provide the effect of trip-free operation of the circuit breaker, the mechanism may be provided with an air-pressure dumping means similar to that disclosed in the aforementioned copending application of J. M. Cumming and R. C. Cunningham, Serial No. 410,686. The air-pressure dumping means causes quick collapse of air pressure in the cylinder on the working side of the piston whenever the trip device 81 is operated, by instantaneously dumping the pressure air in the cylinder to atmosphere to thereby permit quick reversal and high-speed initial opening movement of the circuit breaker unimpeded by back pressure. The air-pressure dumping means comprises large air-pressure dumping ports 115 in the side wall of the cylinder 29 at a point substantially midway between the end positions of the piston 103. These ports are adapted to be connected to atmosphere through a passage formed in a dump valve-housing 117 (Fig. 2) secured to the cylinder 29. This dumping passage is normally closed by a piston type pneumatically-operated dump valve 119 which is slidably mounted in a valve cylinder 121 formed in the dump-valve housing 117. The dump valve 119 is biased closed by a spring 123 disposed in the valve cylinder. Opening of the dump valve 119 is controlled by a pilot valve 125 which is operated by the armature 87 of the trip device 81. When the trip device 81 is energized to trip the circuit breaker the armature 87, in addition to releasing the circuit-breaker latching means, also substantially simultaneously opens the pilot valve 125 thereby establishing communication between the space of the cylinder 29 and the top space of the dump-valve cylinder 121 above the piston-type valve 119, through a passage 127 (Fig. 1) and a pipe 129 (Fig. 2). The pressure air in the circuit-breaker operating cylinder 29, if there is any compressed air in the cylinder at this time, is directed to the top of the piston-type dump valve 119, and initiates opening movement of the dump valve. As soon as this dump valve is cracked open a small amount, the pressure air begins to flow from the cylinder 29 through the dump ports 115 and partially-open dump valve directly to atmosphere, and the pressure of this air quickly completes the opening movement of the dump valve 119. Pressure air in the operating cylinder 29 above the operating piston is thus very quickly dumped directly to atmosphere thereby facilitating quick reversal of the circuit breaker and its operating piston and high speed initial opening movement thereof.

The dump ports 115 are so located intermediate the end positions of the breaker-operating piston that they will be closed off from the upper portion of the cylinder space by the operating piston after the circuit breaker has opened a predetermined distance sufficient to interrupt the circuit. This permits quick automatic reclosing operation of the circuit breaker to be initiated before the breaker reaches the full-open position by energizing the control-valve device 113 to admit compressed air to the operating cylinder before the breaker reaches full-open position.

The operating mechanism is operable to produce normal closing operation of the circuit breaker starting from the full open-circuit position and is also operable to effect quick automatic reclosing operations of the circuit breaker

wherein the reclosing movement is initiated at an intermediate point in the opening stroke of the breaker after the circuit is interrupted but before the breaker reaches the full open position, or at least by that time. The control circuits for controlling the operation of the control electromagnet of the control valve-device 113 and the trip device 81 may be the same as the control circuits disclosed in the aforementioned copending application Serial No. 410,686. These control circuits have not been shown in this application as they are not necessary for a complete understanding of the present invention. It is believed sufficient to state that the tripping electromagnet 81 is energized in response to an overload or short circuit in the main circuit and can also be energized by a manual trip-control switch. For quick automatic reclosing operations, the electromagnet which controls the inlet control-valve device 113 is arranged to be automatically energized by an auxiliary switch at an intermediate point in the opening stroke of the breaker to cause the valve to admit compressed air to the operating cylinder at the proper time. The auxiliary switch is adjustable so that regular automatic reclosing operation from the full open position may be attained if desired. The electromagnet of the control valve-device 113 may also be energized by a manual closing-control switch.

In accordance with the present invention, the operating mechanism is provided with an improved combination intake and exhaust valve-device 113 for admitting compressed air to the operating cylinder for effecting closing of the breaker, and for also rapidly venting the cylinder directly to atmosphere to facilitate quick reversal and high-speed operation of the circuit breaker and its operating means.

The control valve-device 113 comprises a valve-housing 135 which is secured to the side of the main cylinder casting 27 by a plurality of bolts (not shown), a suitable sealing gasket being provided in the joint. The valve-housing has a chamber or opening 131 which communicates with the interior of the air storage-tank 111, and an inlet-passage 139 communicating with the inlet-port 141 in the upper end of the breaker operating cylinder 29. The flanged neck of the air storage-tank 111 is secured to the valve-housing 135 by a plurality of bolts (not shown), a suitable sealing gasket being provided to make the joint air-tight. A main inlet valve-element 143 disposed in the valve-housing has a stem 145 slidably mounted in a guide sleeve 146 carried by a bushing 147. The bushing is threaded in an opening in the housing between chamber 137 and the inlet-passage 139 and this bushing serves as a valve-seat for the inlet valve-element 143. The guide-sleeve 146 is connected to the bushing by a plurality of spider-arms which permit the compressed air to flow when the valve is open. The inlet valve-element is biased to closed position to close the inlet-passage, by a helical compression-spring 149 which surrounds the guide-sleeve, the lower end of the spring bearing on the spider arms of the bushing 147 and the upper end bearing against a spring-support 151 secured to the upper end of the valve-stem. The main inlet-valve is adapted to be opened by means of a valve-piston 153 to open the inlet-passage and admit compressed air to the upper end of the cylinder 29 to close or automatically reclose the circuit breaker. The valve-piston 153 is movable in a valve-cylinder formed in the valve-housing and this valve-piston is biased upwardly to an

inoperative position against the head of the cylinder by means of a helical compression-spring 155 which surrounds a portion of the valve-spring and is disposed between the underside of the valve-piston 153 and a shoulder formed in the valve-housing.

The inlet valve-operating piston 153 is adapted to be moved downwardly to open the main inlet-valve, by compressed air from the tank 111 through passages 157, 159 and 161 in the valve-housing. The air-passages 157 and 159 communicate with cooperating passages in a pilot valve-housing 163 which is secured to the main valve-housing 135. Communication between the air-tank 111 and the top of the valve-piston 153 is normally shut off, however, by a pilot-valve 165 disposed in the pilot valve-housing 163. The pilot-valve 165 is biased to closed position against its seat by a compression-spring 167 and is adapted to be operated to open position to cause air-pressure to open the main inlet-valve, by means of an electromagnet 171 upon energization thereof.

The control valve-device 113 is also adapted to very rapidly vent the breaker-operating cylinder 29 directly to atmosphere when the inlet valve-element is closed in order to facilitate quick reversal of movement of the breaker and its operating piston and high-speed opening operation of the breaker retarded by back pressure in the operating cylinder. For this purpose, the control valve-device 113 is provided with a large exhaust-passage 173, at least as large in cross section as the inlet-passage 139 and inlet port 141. The exhaust-passage 173 communicates directly with the inlet passage and inlet port, and is normally opened to atmosphere by an exhaust valve-element 175. The exhaust valve-element 175 is substantially piston shaped and of hollow construction to make it light in weight, and this valve-element is slidably mounted in a transverse opening provided in a housing 177 which is secured to the housing 135. The housing 177 may be formed integral with the housing 135 if desired. The exhaust valve-element 175 is biased to open position as shown by a helical compression-spring 179 disposed in the opening of the housing section. In the open position, the exhaust valve-element opens the exhaust-passage 173 to atmosphere through the exhaust-port 181. The exhaust valve-element 175 is arranged to be pneumatically operated to closed position to close the exhaust-passage 173 upon opening of the pilot-valve 165, and for this purpose is provided with a piston-portion 183 of reduced cross-section which slides in a cylinder 185 in the housing-section 177. Upon opening of the pilot-valve 165, compressed air is admitted from the tank 111 to the head of the exhaust valve-piston 183 through the passages 157, 159 and a passage connecting 159 to the head of the cylinder 185. The exhaust-valve 175 and the actuating piston 153 of the inlet-valve are pneumatically interlocked by the passage 161 so that upon opening of the pilot-valve 165 closing operation of the exhaust-valve 175 will be initiated before opening of the inlet-valve 143. Compressed air is first admitted to the piston 183 of the exhaust-valve and as the exhaust-valve 175 closes, the piston 183 uncovers the passage 161 so that compressed air is then admitted to the top of the actuating piston 153 of the inlet-valve 143 to effect opening of the inlet-valve. This prevents loss of compressed air through the exhaust-passage.

The pilot-valve 165 has an exhaust-valve 187

connected thereto which closes when the pilot-valve 165 opens and opens when the pilot-valve closes to vent the valve-cylinder of the inlet valve-piston 153 and the valve-cylinder 183 to atmosphere to allow the springs to quickly close the inlet-valve 141 and open the exhaust-valve 175 upon deenergization of the pilot valve-electromagnet 171. The inlet-valve 143 will close slightly before opening of the exhaust-valve 175. A push button 188 is provided on the electromagnet 171 for manually operating the pilot valve to open position to effect closing of the circuit breaker.

The operation of the circuit-breaker mechanism is briefly as follows: Assuming the circuit breaker is in the open position shown in Fig. 1, closing of the circuit breaker is effected by closing a manual control-switch to effect energization of the electromagnet 171 of the control valve-device. When the electromagnet 171 is energized, the pilot-valve 165 opens and admits compressed air from the tank 111 to the piston 183 of the exhaust-valve 175 quickly closing the exhaust-valve. As the exhaust-valve 175 closes the piston 183 uncovers the passage 161, thereby admitting compressed air to the actuating piston 153 to open the main inlet-valve 143. Compressed air is thereupon admitted from the tank 111 directly to the upper end of the main operating cylinder 29 driving the operating piston 103 downwardly to the bottom of the cylinder to effect closing of the circuit breaker. As soon as the breaker reaches closed position, the electromagnet 171 is deenergized and the pilot-valve 165 closes to cause the main inlet-valve 143 to quickly close and the exhaust-valve 175 to quickly open. Opening of the exhaust-valve 175 quickly vents the cylinder 29 directly to atmosphere so that there will be substantially no back pressure to retard opening of the circuit breaker. If there is no fault condition, such as a short circuit, in the main circuit at the time the circuit is closed by the breaker, the circuit breaker will be latched closed and held closed by the latching means 51-65. However, if an overload or short-circuit condition exists, the trip-device 81 will be energized as soon as the circuit breaker closes the circuit. Operation of the trip device causes release of the latching means 51-67 and simultaneous opening of the dump pilot-valve 125. Upon opening of the pilot-valve 125, the pressure air in the operating cylinder 29 immediately opens the dump-valve 119 quickly collapsing the air pressure in the cylinder. As a result, the movement of the circuit breaker is quickly reversed as soon as it reaches closed position and the circuit breaker opens at high speed unretarded by back pressure in the cylinder. The dump-valve 119 opens an instant before the inlet-valve 143 closes and the exhaust-valve 175 opens, thus facilitating quick reversal and high speed initial opening of the breaker. During the first part of the opening movement, the cylinder 29 is vented both by the dump-valve 119 and the exhaust-valve 175, and during the remainder of the opening stroke after the dumping ports 115 are closed by the piston, venting takes place through the exhaust-valve.

Assuming the circuit breaker is standing in closed position and an overload or short circuit occurs in the main circuit, the trip-device 81 will be energized causing the latching means 51-67 to release the circuit breaker whereupon the circuit breaker is operated at high speed toward open position by its opening spring 15. Although the dump pilot-valve 125 is operated simultaneously with the release of the circuit-

breaker latching means, there is no compressed air in the operating cylinder at this time since the cylinder has been vented by the exhaust-valve 175, consequently, the dump-valve 119 does not open. As the piston moves upwardly, the air above the operating piston is rapidly exhausted to atmosphere through the open exhaust-passage 173 so that high-speed opening operation of the breaker is obtained unretarded by back pressure in the cylinder 29.

If the breaker control circuit has been set for quick automatic reclosing, the electromagnet 171 will be energized at a predetermined intermediate point in the opening stroke causing compressed air to instantly close the exhaust valve 175 and open the inlet valve 143, thereby admitting compressed air to the cylinder 29 to initiate reclosing operation of the breaker before the breaker reaches the full open position. When the breaker reaches the closed position, the electromagnet is deenergized and the inlet-valve 143 closes and the exhaust-valve 175 opens. If the fault condition is cleared by the time the breaker closes, the circuit breaker will be latched closed and held closed by the latching means 51-67. However, if the overload or short circuit-condition is still present at the time the circuit breaker recloses the circuit, the trip-device 81 will be again energized to cause release of the latching means 51-67 and opening of the dump pilot-valve 125. The pressure air in the cylinder will immediately open the dump-valve 119 and cause quick collapse of pressure in the cylinder 29. As a result, the movement of the circuit breaker will be quickly reversed and opening operation of the circuit breaker by its opening spring will take place at high speed unretarded by back pressure in the cylinder 29.

Although the dump valve 119 and dumping ports 115 are desirable to help provide for very high speed reversal of the circuit breaker and its operating piston and to provide very high speed initial opening movement of the breaker, they may be omitted if desired as the large exhaust passage and quick acting exhaust valve of the control valve mechanism 113 provide for quick reversal and good high speed opening operation without the dump valve and dumping ports. The circuit breaker and operating piston can be quickly reversed and opened at high speed from any point in the closing stroke by closing of the pilot valve since the closing of the pilot valve will cause the valve device to quickly shut off the flow of compressed air to the breaker cylinder and fully and rapidly vent the cylinder directly to atmosphere.

The improved control valve device 113 may be applied to other types of pneumatic circuit breaker operating mechanisms. In the case of a double acting pneumatic mechanism where the circuit breaker is both opened and closed by compressed gas, each end of the cylinder can be provided with the control valve device of the present invention. The control valve device disclosed can also be used with advantage in a pneumatic operating mechanism embodying a mechanically trip free linkage or lever system to permit quick reverse movement of the piston in its resetting direction to reset the trip free linkage.

The provision of the pneumatic operating mechanism with the improved control valve device disclosed provides for quick reversal of operation and high speed operation of the circuit breaker. The large exhaust passage and exhaust valve element function to rapidly vent the break-

er operating cylinder directly to atmosphere when the inlet valve element closes. The device is simple and compact and the valve elements thereof respond and operate very quickly through relatively short strokes, and only a small amount of electrical control energy is required. The arrangement is such that there is no wastage or leakage of compressed air from the valve, due to the proper sequence of operation of the valve elements.

While the invention has been disclosed in accordance with the patent statutes, it is to be understood that various changes in the structural details, combinations, and arrangement of parts may be made without departing from the essential features of the invention.

I claim as my invention:

1. In an electric circuit breaker having relatively movable contacts, operating means therefor including a cylinder and a piston therein operatively related with the breaker for closing the breaker, a source of compressed gas, a control valve device associated with said cylinder for admitting compressed gas to said cylinder to close the breaker and for also rapidly venting said cylinder directly to atmosphere, said valve device having an inlet passage, a large exhaust passage at least as large as said inlet passage for rapidly venting said cylinder directly to atmosphere, an inlet valve element biased to close said inlet passage, an exhaust valve element operable independently of and movable relative to said inlet valve element and biased to open said exhaust passage, actuating means operable when energized to cause quick closing of said exhaust valve and opening of said inlet valve to admit compressed gas to said cylinder for closing said breaker, and means for delaying opening of the inlet valve until after closing movement of the exhaust valve is initiated.

2. In an electric circuit breaker having relatively movable contacts, operating means therefor including a cylinder and a piston therein operatively related with the breaker for closing the breaker, a source of compressed gas, a control valve device associated with said cylinder for admitting compressed gas to said cylinder to close the breaker and for also rapidly venting said cylinder directly to atmosphere, said valve device having an inlet passage, a large exhaust passage at least as large as said inlet passage for rapidly venting said cylinder directly to atmosphere, a pneumatically operated inlet valve element biased to close said inlet passage, an exhaust valve element movable relative to said inlet valve element and biased to open said exhaust passage, said exhaust valve element controlling the admission of compressed gas to operate said inlet valve and actuating means operable when energized to cause quick closing of said exhaust valve and opening of said inlet valve to admit compressed gas to said cylinder for closing said breaker and spring means biasing said valve elements to quickly close said inlet valve element and open said exhaust valve element upon deenergization of said valve actuating means.

3. In an electric circuit breaker having relatively movable contacts, operating means therefor including a cylinder and a piston therein operatively related with the breaker, a source of compressed gas, a control valve device associated with said cylinder for admitting compressed gas to said cylinder to actuate said piston in one direction and for also rapidly venting said cylinder directly to atmosphere to permit high speed

reverse movement of said piston, said valve device having an inlet passage, a large exhaust passage, at least as large as said inlet passage for rapidly venting said cylinder directly to atmosphere, an inlet valve element operable by compressed gas and biased to close said inlet passage, an exhaust valve element biased to open said exhaust passage and movable relative to said inlet valve element to close said exhaust passage and admit compressed gas to operate said inlet valve, actuating means operable when energized to quickly close said exhaust valve element and cause opening of said inlet valve element for effecting closing operation of the breaker, and means controlling the energization of said valve elements to initiate closing of said exhaust valve element prior to opening of said inlet valve element.

4. An operating mechanism of the pneumatic type for an electric circuit breaker comprising a cylinder and a piston therein for operating the circuit breaker, a source of compressed gas, a control valve device associated with said cylinder arranged to admit compressed gas to said cylinder for moving said piston in one direction to operate said circuit breaker and to also rapidly vent said cylinder directly to atmosphere for permitting high speed reverse movement of said piston, said valve device having an inlet passage through which compressed gas is admitted to said cylinder, a large exhaust passage at least as large as said inlet passage for rapidly venting said cylinder directly to atmosphere, an inlet valve element biased to close said inlet passage and operable by compressed gas to open said inlet passage, an exhaust valve element operable by compressed gas mechanically independently of said inlet valve to closed position and movable relative to said inlet valve element, spring means for biasing and quickly moving said inlet valve element to closed position and said exhaust valve element to open position, compressed gas actuating means for quickly closing said exhaust valve element and opening said inlet valve element to admit compressed gas to said cylinder, and means for controlling the admission of compressed gas to said valve elements to initiate closing of said exhaust valve element prior to opening said inlet valve element, and an electromagnetically controlled pilot valve for admitting compressed gas to said valve actuating means.

5. An operating mechanism of the pneumatic type for an electric circuit breaker comprising a cylinder and a piston therein operatively related to the circuit breaker for operating said circuit breaker, a source of compressed gas, a control valve device associated with said cylinder for admitting compressed gas to said cylinder to move said piston in one direction and for also rapidly venting said cylinder directly to atmosphere to permit high speed reverse movement of said piston, said valve device having an inlet passage through which compressed gas is supplied to said cylinder, a large exhaust passage at least as large as said inlet passage for rapidly venting said cylinder directly to atmosphere, an inlet valve element biased to normally close said inlet passage and operable by compressed gas to open said inlet passage, an exhaust valve element movable relative to said inlet valve element and biased to open said exhaust passage, spring means for biasing and quickly closing said inlet valve element, piston means operable by compressed gas to quickly close said exhaust valve element and to admit compressed gas to the inlet valve to open

said inlet valve element, and an electromagnetically operated pilot valve for controlling the flow of gas to said valve piston means.

6. A pneumatic operating mechanism for an electric circuit breaker comprising a latch for holding said circuit breaker closed, means for tripping said circuit breaker open, a cylinder and a piston therein for closing said circuit breaker, a source of compressed gas for operating said piston to close said circuit breaker, a control valve device associated with said cylinder arranged to admit compressed gas to said cylinder for actuating said piston to close the breaker, and to also rapidly vent said cylinder directly to atmosphere to permit high speed reverse movement of said piston, said valve device having an inlet passage for admitting gas to said cylinder, a large exhaust passage at least as large as said inlet passage for rapidly venting said cylinder directly to atmosphere, a pneumatically operable inlet valve element spring biased to close said inlet passage, an exhaust valve element operable independently of and movable relative to said inlet valve element and spring biased to open said exhaust passage, said exhaust valve having a portion for controlling the admission of compressed gas to operate said inlet valve, compressed gas actuating means operable to quickly close said exhaust valve element and open said inlet valve element to admit compressed gas to said cylinder for closing said circuit breaker, means for delaying opening of said inlet valve element until after closing movement of said exhaust valve element is initiated, and an electromagnetically controlled pilot valve operable when energized to admit compressed gas to said valve actuating means and when deenergized to vent said valve actuating means to atmosphere.

7. In an electric circuit breaker having relatively movable contacts, operating means therefor including a cylinder and a piston therein for operating the circuit breaker, a source of fluid under pressure, and a control valve device associated with said cylinder for admitting fluid under pressure to said cylinder to operate said piston and for also rapidly venting said cylinder directly to atmosphere, said valve device having an inlet passage, a large exhaust passage at least as large as said inlet passage for rapidly venting said cylinder to atmosphere, an inlet valve element biased to close said inlet passage, an independently movable exhaust valve element biased to open said exhaust passage, said valve elements being actuated by fluid pressure, means on said exhaust valve for controlling the admission of fluid under pressure to operate said inlet valve, and an electromagnetically actuated pilot valve for admitting fluid under pressure to actuate said exhaust valve element to closed position and to admit fluid under pressure to operate said inlet valve element to open position to thereby admit fluid under pressure to said cylinder for operating said circuit breaker.

8. A pneumatic operating mechanism for an electric circuit breaker comprising a cylinder and a piston therein for operating said circuit breaker, a source of compressed gas, a control valve device connected to said cylinder for admitting compressed gas to said cylinder to move said piston in one direction and for also rapidly venting said cylinder directly to atmosphere to permit high speed reverse movement of said piston, said control valve device having an inlet passage through which compressed gas is admitted to said cylinder, a large exhaust passage at least as large

as said inlet passage and communicating therewith for rapidly venting said cylinder directly to atmosphere, an inlet valve element biased to close off said inlet passage from said source, an exhaust valve element movable relative to and mechanically independently of said inlet valve element and biased to open said exhaust passage, spring means for quickly closing inlet valve element and for quickly opening said exhaust valve element, and compressed gas actuating means controlled by an electromagnetically operated pilot valve for quickly closing said exhaust valve element and opening said inlet valve element.

9. A pneumatic operating mechanism for an electric circuit breaker comprising a cylinder and an operating piston therein for operating said circuit breaker, a source of compressed gas, a control valve device associated with said cylinder for admitting compressed gas to said cylinder to move said piston in one direction and for also rapidly venting said cylinder directly to atmosphere to permit high speed reverse movement of said piston, said valve device having an inlet passage through which compressed gas is admitted to said cylinder, a large exhaust passage communicating with said inlet passage for rapidly venting said cylinder directly to atmosphere, an intake valve element biased to close off said inlet passage from said source, an independently movable piston type exhaust valve element biased to open said exhaust passage, a piston for actuating said inlet valve to open position, and means for admitting compressed air first to said exhaust valve element to close it and then admitting compressed air to said intake valve piston to open said intake valve.

10. A pneumatic operating mechanism for an electric circuit breaker comprising a cylinder and an operating piston therein for operating said circuit breaker, a source of compressed gas, a control valve device associated with said cylinder for admitting compressed gas to said cylinder to move said piston in one direction for operating the circuit breaker and for also rapidly venting said cylinder directly to atmosphere to permit high speed reverse movement of said piston, said valve device having an inlet passage through which compressed gas is admitted to said cylinder, an inlet valve biased to close said passage and having a piston means actuated by compressed gas to open said inlet valve, a large exhaust passage for rapidly venting said cylinder directly to atmosphere, an exhaust valve mounted for movement independently of said inlet valve and biased to open said exhaust passage, said exhaust valve having piston means actuated by compressed gas to open said exhaust valve, means including an electromagnetically actuated pilot valve for admitting compressed gas to said exhaust valve piston means to close said exhaust valve, and a passage uncovered upon closing movement of said exhaust valve for admitting compressed gas to said inlet valve piston means to open said inlet valve.

11. In an electric circuit breaker having relatively movable contacts, operating means therefor including a cylinder and a piston operatively related with the movable contact, a source of fluid under pressure, a control valve device associated with said cylinder having a normally closed inlet passage operable to admit fluid under pressure to said cylinder for closing said circuit breaker and having a normally open large exhaust passage at least as large as said inlet passage, closed when said inlet passage is open and open when

said inlet passage is closed for rapidly exhausting said cylinder directly to atmosphere, a latch for holding said circuit breaker closed, said cylinder having a large fluid dumping port intermediate the end positions of said piston, a dump valve normally closing said dumping port operable to open position for instantaneously exhausting said cylinder to atmosphere to permit high speed initial opening movement of said piston, and

means for releasing said latch and for substantially simultaneously controlling operation of said dump valve, said piston closing off said dumping port from the cylinder space on the working side of said piston after it passes an intermediate point in its opening stroke so that fluid under pressure can be admitted to said cylinder to quickly reclose the circuit breaker.
